(57) **CLAIM**

The ornamental design for a concrete form bolt template, as shown and described.

DESCRIPTION

FIG. 1 is a top, front right perspective view of a concrete form bolt template showing our new design;

FIG. 2 is a top, front left perspective view thereof;

FIG. 3 is a top, rear right perspective view thereof;

FIG. 4 is a top, rear left perspective view thereof;

FIG. 5 is a front side view thereof;

FIG. 6 is a rear side view thereof;

FIG. 7 is a right view thereof;

FIG. 8 is a left view thereof;

FIG. 9 is a top view thereof;

FIG. 10 is a bottom view thereof;

FIG. 11 is a left side view of a portion of my concrete template;

FIG. 12 is a top, front left perspective of a portion of my concrete template; and,

FIG. 13 is a bottom, front left perspective of a portion of my concrete template.

The broken lines are for the purpose of illustrating portions of the concrete template and form no part of the claimed design.
